UNITED STATES PATENT OFFICE.

ALBERT PARR, OF KENOSHA, WISCONSIN, ASSIGNOR OF ONE-HALF TO OTTO F. WINDORF, OF KENOSHA, WISCONSIN.

BAR-MAT.

1,112,649.

Specification of Letters Patent.

Patented Oct. 6, 1914.

Application filed March 29, 1913. Serial No. 757,493.

To all whom it may concern:

Be it known that I, ALBERT PARR, a citizen of the United States, and resident of Kenosha, in the county of Kenosha and State of Wisconsin, have invented new and useful Improvements in Bar-Mats, of which the following is a description, reference being had to the accompanying drawings, which are a part of this specification.

10 This invention relates to mats for use behind bars and in similar places where it is desired to keep the feet off of a wet floor or where a resilient floor surface is desired, such as on cement floors.

15 With the above and other objects in view the invention consists in the bar mat as herein claimed and all equivalents.

Referring to the accompanying drawings in which like characters of reference indicate the same parts in different views: Figure 1 is a plan view of a bar mat constructed in accordance with this invention; Fig. 2 is a perspective view of a portion thereof partially rolled for removal; Fig. 3 is an end view showing the yielding character of the mat; and, Fig. 4 is a detail view showing the manner of connecting the slats to the bearing strips.

In these drawings 10 indicates a number 30 of hardwood slats preferably rounded at their upper edges as shown and arranged parallel at a short distance apart and secured to flexible bearing strips 11 of canvas, leather or other material which will not 35 be affected by moisture on the floor and which will permit of the mat being rolled in the manner shown in Fig. 2. The slats are of much greater width than height and being of resilient material and supported at 40 spaced points by the bearing strips 11 are

capable of yielding to the weight of a person standing thereon. The slats are preferably secured to the bearing strips 11 by means of wood screws 12 passing through the bearing strips and then into the slats. A 45 mat of this construction when used behind the bar will keep the bartender's feet dry even though the floor is wet, as usual, and furthermore, instead of having an unyielding concrete surface to stand upon he has a 50 more comfortable yielding surface provided by the slats held above the floor by the bearing strips at intervals so that they may spring between the bearing strips in the manner shown in Fig. 3. 55

While the mat of this invention is inexpensive and durable, it is further very desirable for the use intended by reason of its flexible nature which permits of its being rolled into a light bundle easily removed for 60 cleaning the floor.

What I claim as new and desire to secure by Letters Patent is:

A yielding rolling mat, comprising lengthwise extending bearing strips of canvas or 65 the like spaced apart, and cross-wise extending parallel slats of resilient material of a width greatly exceeding their height and mounted on top of and secured to the bearing strips, the bearing strips constituting 70 spaced supports for the resilient slats permitting the slats to yield between them to form a spring like floor covering.

In testimony whereof, I affix my signature, in presence of two witnesses.

ALBERT PARR.
